UNITED STATES PATENT OFFICE

2,471,510

PANEL

John B. Anthony, Berkeley, Calif., assignor to
 Kaiser Engineers, Oakland, Calif., a corporation
 of California

Application October 19, 1945, Serial No. 623,223

4 Claims. (Cl. 108—6.5)

1

This invention relates to building structures, and more particularly it relates to a panel for use in wall and roof structures of buildings.

Among the objects of the invention is the provision of a light weight, fire resistant panel which is economic and readily constructed.

Another object of the invention is the provision of a wall and roof panel provided with means for interlocking and aligned attachment with adjacent units.

A further object is to provide a sectional wall or roof element adapted for external use, which in cooperation with a plurality of similar units, will provide an effective seal against the elements, as well as against heat transfer.

According to the invention there is provided a panel for use in wall and roof structures comprising a metal sheet adapted for exterior use and a cementitious slab, said metal sheet having a corrugated portion extending along its length and said slab having means on at least two opposed edges for alignment with slabs in adjacent panels, and means for fastening said metal sheet to said slab in face to face relation. The invention also contemplates the use of a fibrous sheet for acoustical purposes and insulation, as well as ornamentation. In building structures a plurality of wall and roof panels in aligned relation are each fastened to the framework of the building. These and other objects of the invention will be apparent from the specification and drawings, which illustrate a preferred embodiment of the invention.

In the drawings:

Figure 1 represents a section of a wall structure showing a plurality of assembled panels; and

Figure 2 represents an enlarged sectional view of one panel taken along line 2—2 of Figure 1;

Figure 3 is a view in perspective of a panel assembly slab.

The panel assembly when erected generally comprises a corrugated metal sheet 11 and a cementitious slab 12 fastened to an exterior supporting framework 13 preferably composed of substantially parallel structural members by means of suitable bolts 14. The corrugated metal sheet 11 is adapted to serve as an exterior member and provide protection against the elements by virtue of its weather-proofing and water-proofing characteristics. The sheet 11 may be of any desired thickness depending upon the unsupported length of the sheet and the extent to which it is needed for structural purposes. As shown in the drawings, it is adapted to rest against the slab 12 in face to face relation there-

2

with and advantageously is of the same length as the slab. Its width may vary and a single sheet may extend over the width of the slab or less, or over several slabs. The corrugated portions 15 run the length of the sheet 11 and are preferably rather large in cross-section so as to produce a cellular-like panel of sheet 11 and slab 12 which contributes stiffness to the sheet and an ornamental appearance.

10 The slabs 12 are preferably precast, reinforced, rectangular tile formed of cementitious material such as calcined gypsum. In the preferred form shown in the drawings, the slabs 12 are provided with tongue and groove means, respectively, on 15 opposed edges for the purpose of providing alignment and interlocking with slabs in adjacent panels. Although, it is preferred to provide the tongue and groove arrangement 16 at all edges of slab 12, satisfactory results may be obtained 20 if they are on two opposed edges only. It is also useful to provide the edges of slabs 12 with binders 17 of metal or the like. The binders 17 give the slabs straight edges so that true joints 25 may be had and erection facilitated. The binders 17 also protect the edges of slab 12, particularly where tongue and groove means are used, against chipping, breaking and other damage. The binders 17 also provide a surface to which interior finishing material may be attached. The 30 binders 17 are advantageously inserted in the mold when the slab 12 is cast so that the ends 18 of the binders may be anchored securely.

As stated previously, the cementitious material within the slab is preferably calcined gypsum, although hydraulic cement, clay or other suitable materials may be used. In practice, it is desirable to reinforce the slab 12 so as to insure 35 against failure in use. In the preferred embodiment wire mesh 19 is employed. Obviously mesh 40 19 or whatever other reinforcing means is used is cast integrally with the slab.

The slabs 12 and sheets 11 may be fastened together in any satisfactory fashion. In the embodiment shown in the drawings this is accomplished by providing bolts 14 which pass through 45 holes 20 in slabs 12 and are in turn fastened to supporting framework 13 of the building structure. A recess 21 is provided in the face of slab 12 opposite sheet 11 where the bolt head may 50 rest.

An inner lining 22 may also be used which is adapted to rest against the other face of slab 12. This inner lining 22 may be of any materials 55 which would serve as additional insulation against heat transfer, give improved acoustic

effects, or ornamentation or the like. In the embodiment shown in the drawings the material 22 is fiber glass and is used for acoustic purposes. The fiber glass 22 is held in place by metal screws 23 which extend into slab 12. However, any suitable fastening means may be employed.

It is to be understood that the inner lining 22 is not an essential feature of the invention in all of its uses and, accordingly, may be dispensed with in certain cases.

The present invention has several advantages. It provides a panel assembly which is light in weight, of sturdy construction, has good insulating qualities, is adapted for exterior uses, and which may be readily erected with a minimum of time and expense.

The form of the invention shown herein represents the preferred embodiment thereof although variations may be made within the scope of the appended claims. For example, the corrugated portion of sheet 15 may be reinforced by filling it with gypsum or other cementitious material as shown at 15a.

What is claimed is:

1. An exterior building wall including in combination a plurality of exposed and spaced apart parallel structural members, an interior panel assembly comprising a plurality of interlocking pre-cast slabs of fire resistant material lying adjacent one another and supported by and spaced from said structural members, a longitudinally corrugated exterior sheet interposed between and contacting said structural members and said slabs of said panel assembly and common fastening means for securing said corrugated sheet to said structural members and to said slabs.

2. An exterior building wall including in combination a plurality of exterior and spaced apart parallel structural members, an interior panel assembly comprising a plurality of interlocking pre-cast cementitious slabs lying adjacent one another and adapted to be rigidly supported by said structural members and spaced at a substantially equal distance therefrom, heat insulating and sound absorbing members fastened to the interior surface of said slabs, an exterior corrugated metallic sheet interposed between and contacting said structural members and said slabs of said panel assembly, and fastening means

common to both said panel and said structural members for securing said corrugated sheet to said structural members and to said panel assembly.

3. An exterior building wall including in combination a plurality of spaced apart and substantially parallel exposed support members, an interior panel assembly comprising a plurality of pre-cast interlocking rectangular cementitious slabs lying adjacent one another and supported by and spaced from said support members, a plurality of exterior longitudinally corrugated sheets interposed between said support members and said slabs, the troughs between said sheet and said slabs being filled with cementitious material, and fastening means common to both said slabs and said support members for securing said panel assembly and said sheets to the support members.

4. A structure for a building comprising an exterior supporting framework, a plurality of interiorly disposed slabs of cementitious material, said slabs having means on at least two opposed edges for interlocking engagement with adjacent slabs, protecting metallic binder members covering said edges and fixed to said slabs, an exterior corrugated metallic sheet interposed between and in contact with said slabs and said framework and common fastening means for securing said corrugated sheet to said supporting framework and to said slabs.
